Inventor
Thomas J. McConnoughay

UNITED STATES PATENT OFFICE.

THOMAS J. McCONNOUGHAY, OF HARRISONVILLE, MISSOURI.

HAT AND COAT RACK.

SPECIFICATION forming part of Letters Patent No. 371,205, dated October 11, 1887.

Application filed March 22, 1887. Serial No. 231,983. (No model.)

To all whom it may concern:

Be it known that I, THOMAS J. McCONNOUGHAY, a citizen of the United States, residing at Harrisonville, in the county of Cass and State of Missouri, have invented a new and useful Improvement in Hat and Coat Racks, of which the following is a specification.

My invention relates to an improvement in hat and coat racks; and it consists in a certain novel construction and arrangement of parts, fully set forth hereinafter, and specifically pointed out in the claims.

In the drawings hereto annexed, Figure 1 is a perspective view of the rack. Fig. 2 is a rear view of the base-plate. Fig. 3 is a vertical section on the line *x x*, Fig. 2. Fig. 4 is a section of the horn, line *y y*, Fig. 3.

Referring by letter to the drawings, in which similar letters denote corresponding parts in all the figures, A designates the base-plate of the rack, of any preferred ornamental pattern, having the perforations *a a* therein for the reception of screws to secure the same to the wall or other vertical surface, and B is a coat-peg having a stud, *b*, on the rear end, secured in an opening, B', in the lower end of the plate.

C represent two perforations near the upper end of the plate and joined on the rear side of the plate by a groove, D, and G is a stout wire passed at the ends through the said perforations from the rear side of the plate, with the wire in the rear of the plate resting or fitting in the groove D between the said perforations, and the front ends of the said wire support bent laterally to form hooks.

H designates a horn cut off square at the rear end, and polished and secured to the plate by filling the interior thereof with plaster-of-paris and inserting the ends of the wire G therein while the plaster is soft and pressing the rear or butt end of the horn firmly against the surface of the plate and allowing the said plaster to set.

I is a rod which is passed through aligned openings in the rear end of the horn and riveted at each end on the outside thereof, the object being to prevent the plaster-of-paris, should it become loose, from slipping out of the horn and allowing the said horn to drop, and the ends of the wire G are designed to pass on either side of the said rod.

It will be readily seen that when the plaster which is placed in the horn becomes hard the horn will be held tightly in position, as 55 the hooked ends of the wires G will prevent the said wires from becoming disengaged from the plaster, and the rod I across the end of the horn will prevent the said plaster from slipping out of place. The said wire support is 60 made of very strong wire, and as one of the perforations C is placed vertically over the other it is evident that the horn will be held firmly and securely in place and strongly braced by the position of the wire support from being 65 dragged down by the weight of the article hung on the outer end thereof.

My improved rack is a very useful and an extremely ornamental article, and will be found of great durability, and the manner of 70 constructing the device is novel and extremely simple, and it may be manufactured very cheaply.

Having thus described my invention, I claim—

1. In a rack, the plate A, having the perforations C C therein, groove D between the said perforations, and the wire G, to pass at the ends through the said perforations, with the loop of the said wire resting in the said groove 80 D, and the horn H, to be secured on the ends of the said wire, substantially as described.

2. In a rack, the plate A, having the support G projecting therefrom, combined with the horn H, having a short rod, I, secured transversely therein near the butt-end, said horn being adapted to be secured on the said support G, substantially as described.

3. In a rack, the plate A, having a support, G, thereon, combined with the horn H, adapted 90 to be filled with plaster-of-paris to receive the end of the said support, and the rod I, secured in aligned openings near the rear end of the horn, for the purpose set forth, substantially as described.

In testimony that I claim the foregoing as my own I have hereto affixed my signature in presence of two witnesses.

THOMAS J. McCONNOUGHAY.

Witnesses:

JOHN C. BYBEE,
F. H. CLARK.

Correction in Letters Patent No. 371,205.

It is hereby certified that the name of the patentee in Letters Patent No. 371,205, granted October 11, 1887, for an improvement in "Hat and Coat Racks," was erroneously written and printed "Thomas J. McConnoughay," whereas said name should have been written and printed *Thomas J. McConnaughay*; and that said Letters Patent should be read with this correction therein that the same may conform to the record of the case in the Patent Office.

Signed, countersigned, and sealed this 8th day of November, A. D. 1887.

[SEAL.]

D. L. HAWKINS,
Acting Secretary of the Interior.

Countersigned:

R. B. VANCE,
Acting Commissioner of Patents.
